UNITED STATES PATENT OFFICE.

HARRY D. SMILEY, OF ALBIA, IOWA.

POWDER-CHARGING DEVICE.

1,306,316.

Specification of Letters Patent. Patented June 10, 1919.

Application filed August 10, 1918. Serial No. 249,271.

To all whom it may concern:

Be it known that I, HARRY D. SMILEY, a citizen of the United States, residing at Albia, in the county of Monroe and State 5 of Iowa, have invented certain new and useful Improvements in Powder-Charging Devices, of which the following is a specification, reference being had to the accompanying drawings.

10 This invention relates to an improved powder charging device, and has for its primary object to provide a device primarily designed for use by miners in charging a hole or bore formed in the face of the mine 15 wall with powder, and then securely tamping the hole.

It is another and more particular object of the invention to provide a device for the above purpose embodying a tubular member 20 to receive the powder charge and the dynamite cartridge or other explosive, a tubular rod connected to said member, an expelling plunger arranged within said tubular member, an operating rod therefor provided with 25 a scraper disk, and means for locking said rod against movement relative to the tubular rod to retain said plunger against movement for use as a tamping head, or to permit of the use of the scraping disk.

30 It is also a further general object of my invention to provide a device for the above purpose which is relatively simple and durable in its construction, as well as efficient and reliable in operation, and capable of 35 manufacture at comparatively small cost.

With the above and other objects in view, the invention consists in the improved combination, construction and relative arrangement of the several parts as will be herein- 40 after more fully described, subsequently claimed and illustrated in the accompanying drawings in which similar reference characters designate corresponding parts throughout the several views, and wherein:—

45 Figure 1 is a side elevation, the tubular charge receiving member being shown in section;

Fig. 2 is a similar view showing the ejecting plunger locked in the tubular member 50 for use as a tamper;

Fig. 3 is an enlarged detail longitudinal section showing the locking means;

Fig. 4 is a side elevation illustrating the manner of using the scraping device;

Fig. 5 is a fragmentary longitudinal section taken on the line 5—5 of Fig. 1; and 55

Fig. 6 is a detail perspective view of the scraper.

Referring in detail to the drawings, 5 designates a tubular sheet metal charge receiving member having opposed longitudinally extending arms 6 on one end thereof. These arms are pivotally engaged upon the bolts 7 fixed in opposite sides of a sleeve 8, which is threaded upon one end of a tubular 60 rod 9. This rod may be made up in sections of suitable length, coupled together, and is provided at its other end with a sleeve 10 having a tapered threaded bore 11.

A rod 12 is longitudinally movable 70 through the tubular rod 8 and to one end of this rod, a plunger 13 is pivotally connected, as at 14, said plunger being freely movable within the tubular charge receiving member 5. This plunger 13 may be of 75 any preferred construction.

The other end of the rod 12 is threaded and to the same a coupling member 15 is connected. The other end of said member is exteriorly threaded for engagement by 80 the interior threads on one end of the sleeve 16 in which one end of the rod 17 is threaded. The other end of this rod is formed with a disk-shaped scraper blade 18, which projects at right angles to said rod and from 85 one side thereof.

In the use of the device, the rod 12 is moved longitudinally through the rod 9 and the member 15 is threaded into the tapered bore 11 of the sleeve 10, thereby locking 90 the rods 9 and 12 against relative movement, then the device may be used as a scraping tool, as will be hereinafter set forth. In the boring of the hole to receive the explosive charge, the loosened material 95 is scraped or removed from the hole by means of the scraper blade 18 in the manner illustrated in Fig. 4 of the drawings.

After the hole has been bored to the proper depth, the member 15 is rotated to unlock 100 the rod 12, which is then moved through the rod 9 to position the plunger 13 in the inner end of the tubular member 5. The explosive powder and the dynamite cartridge, together with a suitable tamping material, are then arranged in the member 5 in proper order. The tubular member 5 is now inserted in the hole and the rod 12 105

forced through the rod 9 to cause the plunger 13 to expel or eject the materials into the inner end of the hole. The rod 12 is now again locked, as above explained, 5 against movement relative to the rod 9, with the plunger 13 projecting slightly beyond the outer end of the member 5. The plunger may now be conveniently used for the purpose of packing or tamping the hole, 10 after which said tubular member is withdrawn. Thus, it will be seen that I have devised an improved powder charging and tamping device for use by miners which will be very serviceable and convenient in 15 practical use and will eliminate the necessity of employing a number of separate tools or implements. The device as a whole is comparatively simple in its construction, as well as strong and durable, and can also 20 be manufactured and sold at relatively small cost. It will, of course, be understood that the charge receiving member 5, as well as the rods 8 and 12 can be of any desired length and diameter. It is also to be 25 borne in mind that while I have herein shown and described the preferred construction and relative arrangement of the several parts, the device is nevertheless susceptible of considerable modification therein 30 and I, accordingly, reserve the privilege of adopting all such legitimate changes as may be fairly embodied within the spirit and scope of the invention as claimed.

I claim:

35 1. The combination with a tubular charge receiving member and an ejecting plunger movably mounted therein for ejecting a powder charge therefrom, said plunger having a plunger rod, of a tubular rod connected to one end of said member and in 40 which the plunger rod is axially movable, and means carrying a tool and being adjustably connected to the plunger rod and provided with axial detachable connections 45 with one end of the tubular rod for locking the plunger against movement in the tubular member.

2. In a device of the character described,

a tubular charge receiving member, a tubular rod connected to one end of said member, a second rod movable through the tubular rod, a plunger on one end of the second named rod movable in said tubular member to eject the charge therefrom, and means threaded axially on the other end of the 55 second named rod and being capable of detachably and axially threading into the tubular rod and adapted to lock the second named rod against movement relative to 60 said tubular rod.

3. In a device of the character described, a tubular charge receiving member open at one end, a tubular rod connected to the other end of said member, a second rod movable through the tubular rod, a plunger connected to one end of the second named rod and movable within said tubular member, an interiorly threaded sleeve on the other end of said tubular rod, and a member carried by said second named rod adapted to 65 be threaded within said sleeve to lock the rods against relative movement and retain the plunger in a stationary position relative to the tubular member at the open end of the latter. 75

4. In a device of the character described, a tubular charge receiving member, a tubular rod connected to one end of said member, a second rod movable through the tubular rod, a plunger on one end of said second 80 named rod movable in the tubular member to eject the charge therefrom, a scraper connected to the other end of said second rod, and means for locking the second named rod against movement relative to the tubular rod to retain the plunger in position 85 relative to the tubular member for use as a tamper, or to permit of the use of said scraper.

In testimony whereof I hereunto affix my 90 signature in the presence of two witnesses.

HARRY D. SMILEY.
